UNITED STATES PATENT OFFICE.

FRED A. RUMNEY, OF BOSTON, MASSACHUSETTS, ASSIGNOR TO UNITED SHOE MACHINERY COMPANY, OF PATERSON, NEW JERSEY, A CORPORATION OF NEW JERSEY.

FASTENER-SETTING MACHINE.

1,231,201.

Specification of Letters Patent. Patented June 26, 1917.

Application filed August 17, 1912. Serial No. 715,645.

To all whom it may concern:

Be it known that I, FRED A. RUMNEY, a citizen of the United States, residing at Boston, in the county of Suffolk and State 5 of Massachusetts, have invented certain Improvements in Fastener-Setting Machines, of which the following description, in connection with the accompanying drawings, is a specification, like reference characters 10 on the drawings indicating like parts in the several figures.

This invention relates to machines for setting eyelets, hooks or other fasteners in sheet material, such as cloth or leather, and 15 the invention contemplates the provision of a machine whereby such fasteners may be set rapidly and accurately in corsets or similar articles.

In eyeleting corsets much difficulty has 20 been experienced in properly guiding the work to the setting tools, as the weight of the garment tends to displace the work between successive setting operations so that the eyelets are likely not to be properly 25 alined with a uniform spread from the edge of the corset. An important feature of the invention consists in the provision of a guiding member having an extended supporting surface and a rib so arranged as to 30 support the weight of the garment, preferably by engaging the inner portion of its stiffened edge as it is being fed to the setting tools. By this means the operator is relieved of the necessity of supporting the 35 work as it is fed through the machine, it being only necessary to see that the stiffened edge of the work runs smoothly through the guiding member.

As herein shown the guiding member 40 comprises a trough-shaped work supporting piece arranged with one wall flush with the edge gage of the machine and the other wall spaced from it by a distance equal to the width of the stiffened edge of the garment. 45 The employment of such a guiding member insures that the work shall be directed to the setting tools in a straight line and that the alinement of the eyelets shall be perfect. As 50 herein shown, the position of the supporting rib is adjustable so that the machine may be adapted to handle material with different widths of edge.

An important advantage is derived by 55 mounting the guiding member upon the

edge gage of the machine as in this way the guiding member will be adjusted simultaneously with the edge gage when it is desired to vary the spread of the fasteners from the edge of the work.

As herein shown the work guiding member is embodied in a Duplex eyeleting machine of the type disclosed in Patent No. 934,066 granted September 14, 1909 to G. Goddu, and the combination of a guiding 60 member of the character outlined with such a machine constitutes an important feature of the invention. In a machine of that type, the setting tools are arranged to operate in an oblique path and as the die plate is downwardly inclined, the work has a greater tendency to become displaced than in those machines having a horizontally disposed work plate. The provision of a trough shaped guiding member obviates this difficulty by providing a device upon which the work is suspended during the operation 65 of the machine.

Another important feature of the invention consists in a guiding member arranged 70 with its work supporting face disposed below the plane of movement of a work feeding member together with interposing means between the guiding member and the feeding member for elevating the work and directing it to the feeding member and the setting tools. This arrangement of the parts has proved particularly advantageous 75 in practice, not only in causing the work to run evenly and smoothly to the setting 80 tools but in relieving it from undue strain 85 when subjected to the sudden action of the feeding member.

Another feature of the invention relates 90 to an improved form of presser foot by 95 which work of the class in question may be held and directed to the setting tools in an improved manner and all tendency toward slipping away from the edge gage avoided.

In order to permit the work to be fed 100 rapidly it is necessary to insure that each clenched fastener shall be cleared or stripped promptly from the projecting pilot of the upsetting die and to this end the present invention contemplates, as one feature, the provision of a projection located 105 adjacent to the upsetting die in such position that the work is somewhat bent over it by the setting die in the setting operation. With this construction the work will 110

promptly straighten as soon as released by the setting die and the clenched fastener will be lifted off the pilot so that the work may be moved laterally at once in the feeding operation.

Still another feature of the invention relates to the construction of the setting tools and consists in the provision of a setting die with a center spindle having a cupped end into which the pilot of the upsetting die is adapted to project when the spindle is forced against it. Advantages of this construction are that the setting die and its center spindle are automatically centered relatively to the upsetting die and that the marginal edge of the hole in which the fastener is to be set is engaged by the cupped end of the spindle so that the loose fiber ends are held compactly until they are covered by the clenched fastener. Another advantage of this construction appears in those cases where the chip cut out by the punch is not removed but remains in place in the work, for in that case the chip will be forced into the cupped end of the spindle where it will stick momentarily when the spindle is retracted so that it will be removed from the work by the spindle.

These and other features of the invention will be best understood and appreciated from the following description of a preferred embodiment thereof selected for purposes of illustration and shown in the accompanying drawings, in which—

Fig. 1 is a view in perspective of the operating parts of a duplex eyelet having the present invention embodied therein.

Fig. 2 is an elevation partly in section of the presser foot and work plate.

Fig. 3 is a view in perspective of the die plate.

Fig. 4 is a view in perspective of the parts of the work guiding member.

Fig. 5 is a fragmentary view in perspective showing portions of the spacing mechanisms.

Fig. 6 is a view in cross section of the work guiding member showing a portion of the work.

Fig. 7 is a detail view of the spindle of the setting die and

Fig. 8 is a sectional view on an enlarged scale of the upsetting die and spindles.

As in a machine of Patent No. 934,066 the frame 2 is provided with journals for a horizontal driving shaft 4 upon which is mounted a driving pulley, not shown, and a series of cams which actuate the various parts of the machine. The movable head or frame 12 carries an oppositely disposed pair of setting dies 14 and oppositely disposed punches 16 which coöperate respectively with the double faced upsetting die 20 and cutting block 22 mounted in the die plate 18 which is rigidly secured in the head 12.

The head 12 is pivotally mounted by the pin 24 between the forks of an arm of a bell crank lever 26 pivotally mounted in the machine frame. The other arm of the lever 26 carries a cam roller which runs in a cam 8 on the shaft 4. The cam 8 acting through the lever 26 serves to move the frame 12 rearwardly after the punching operation in order to bring the setting dies into the position formerly occupied by the punches. The setting dies and punches are actuated by an oppositely disposed pair of hammer levers 28, one of which is mounted upon the journal pin 30 in the frame of the machine. The other is similarly mounted below the head 12 but is not visible in the views of the machine shown in the drawings. The levers 28 are actuated by the cam 10 acting upon a cam roller journaled in the piece 32 secured to the rear end of one of the levers.

The work is moved transversely between successive setting operations by laterally swinging the frame 12 about its pivot 24, and this operation is effected by the cam 6 of the shaft 4 acting through the cam lever 34 and a pair of connecting links 36 and 37.

A work plate 38 is mounted in the machine frame adjacent to the die plate 18 when the latter occupies its initial position and upon opposite sides of the work plate are disposed presser feet 40, held yieldingly against the opposite sides of the work plate by springs 42. At their rear ends the springs 42 are secured to a block 44, the forward edges of which constitute edge gages. The work plate 38 has rack teeth 45 cut in its shank and may be adjusted forwardly and rearwardly together with the edge gages and presser feet in order to vary the spacing of the eyelets from the edge of the work.

The work guiding member is formed by a plate 50 having at its upper edge an integral rib 52 notched out at its inner end to receive a portion of the upper edge gage. The rib 52 is secured to the edge gage so that its face extends flush with the face of the edge gage, and the plate 50 is held in place by a link 54 which extends from an ear 56 on the plate to a stationary arm projecting from the machine frame. The inner face of the rib 52 constitutes in effect a continuation of the edge gage and by maintaining the edge of the work in contact with this surface the greatest accuracy is secured in directing the work in its movement to setting position.

On its lower side the plate 50 is slotted and provided with downwardly projecting clamping bolts 68 arranged to extend through the slotted ears 60 of a rib piece 62. The upper surface of the rib piece 62 extends above the surface of the supporting plate 50 and is disposed in parallel relation with the fixed rib 52. By loosening nuts 64

on the clamping bolts 58 the rib piece 62 may be adjusted toward or from the fixed rib 52 and the distance between these two ribs may be made to correspond to the width of the stiffened edge of the work in hand.

The position of the work in the guiding member is well illustrated in Fig. 6 from which will be seen that the two stiffened edges of the corset fit into the trough shaped portion of the guiding member with their outer edges in contact with the face of the upper or fixed rib 52 and their lower edges supported by the inner face of the adjustable rib piece 62. When the work is arranged in this position its entire weight is supported by the upper edge and inner face of the rib piece 62 and in operating the machine, it is necessary only to see that both stiffened edges are kept within the trough shaped guiding member. As the latter is particularly adapted by reason of its characteristic shape to receive these edges, the skill required by the operator is thus reduced to a minimum.

As has been stated above, the feeding movement of the work is produced by swinging the head 12 laterally while the setting dies remain in engagement with a clenched eyelet. The extent of the feeding movement is regulated by a controlling lever 39 by which the transmission links 36 and 37 may be maintained more or less effective to transmit the full swing of the cam lever 34. The controlling lever 39 is arranged to move over a perforated plate 41 in which may be set limiting stop pins 43. Upon the lower end of the pivot of the controlling lever 39 is secured a transversely extending arm 431 to which is attached a tension spring 451 tending normally to swing the arm 431 in the direction to hold the controlling lever 39 in its position of maximum spacing as determined by the left stop pin in Fig. 1. Manually controlled means, which in this case comprise the chain 47 and a treadle, not shown, are connected to the arm 431 so as to swing the arm 431 in opposition to the action of the spring 451 in order that the controlling lever 39 may be temporarily swung into a position of close spacing when so desired. This construction, which it is believed has never before been incorporated in a fastener setting machine, is of great advantage when applied to a Duplex machine of the type herein disclosed, for the reason that it enables the operator to eyelet simultaneously both sides of a corset, setting the upper and lower eyelets with a relatively wide spacing and the intermediate eyelets with a relatively close spacing, while at the same time insuring absolutely the correspondence of the spacing in the two sides.

In order to insure that the work shall not slip forwardly away from the edge gages as it is fed through the machine, it has been

found advantageous to provide the work plate 38 and presser foot 40 with oppositely disposed ribs inclined rearwardly toward the edge gage. In my prior Patent 1,030,833 is disclosed a work plate provided with ribs of this character, but for handling textile material, it has been found that better results are secured by providing not only the work plate but also the active faces of the presser foot with inclined ribs. As the work is drawn between the two sets of inclined ribs it has imparted to it a tendency to move toward the edge gage, being deflected inwardly from its normal path so as to counteract the tendency toward slipping outwardly.

As already intimated, the feeding operation is effected by swinging the head 12 laterally while the setting dies 14 hold the clenched eyelets against the upsetting die 20 in the die plate 18. At the conclusion of this lateral movement the setting dies 14 are retracted and the head 12 together with the die plate 18 is moved transversely in the opposite direction to its initial position. In order to insure that the clenched eyelet shall be promptly disengaged from the projecting pilot of the upsetting die 20 when the setting dies are retracted, the die plate 18 is provided at its end with a thickened portion or bulge 19 which tends to strip the material and the clenched eyelet from the pilot of the upsetting die as soon as the material is released by the setting dies.

In operating upon textile material it is important that the loose fiber ends which are left at the margin of the perforation formed by the punch shall be held compactly together until the eyelet can be clenched upon them, as otherwise the appearance of the work would be marred by loose threads running out from the flange of the eyelet. As herein shown, this defect is obviated by cupping the end of the center spindle 15 of each setting die and making the diameter of the cupped end slightly greater than the diameter of the hole cut by the punch, but slightly less than the diameter of the pilot of the upsetting die. By employing this construction, it will be seen that the margin of each perforation is engaged by the end of the spindle 15 and pressed tightly against the pilot of the upsetting die preliminarily to setting the eyelet, so that there is no possibility of the loose fiber ends being displaced. This action of the center spindle is well shown in Fig. 8.

It sometimes happens that the chip severed by the punch is not removed from the material, but remains in place, and another advantage incident to the construction of the setting spindle 15 is that if a chip is left in place by the punch, it will be forced into the end of the spindle by the pilot of the up-

setting die sufficiently to cause it to stick momentarily in the spindle as is indicated in Fig. 7, so that it will be picked up by the spindle and carried away from the work. 5 The spindle herein shown also contributes to improve the character of the work done by the machine by reason of the fact that it tends to align itself with the pilot of the up-setting die when forced against its convex end. 10

The machine of this invention has been described in connection with corset work particularly but it should be understood that many of its features are useful in machines for setting fasteners in other kinds of work. 15

Having thus described my invention, what I claim as new and desire to secure by Letters Patent of the United States is:—

20 1. A duplex fastener setting machine having, in combination, a stationary elongated channel constructed and arranged to receive the edge portions of two contiguous pieces of work, an edge gage disposed adjacent to one end of the channel, means for separating the two pieces of work as they pass the edge gage, and setting tools for inserting a fastener in each piece of work adjacent to their point of separation. 25

30 2. A duplex fastener setting machine having, in combination, setting tools arranged to operate in an inclined path, a work guiding member having an inclined unobstructed supporting surface extending to a point remote from the setting tools, a longitudinally disposed shoulder at its lower edge over which portions of two superposed pieces of work are suspended while the edges of said pieces rest on the supporting 35 surface, and means for separating the two pieces of work after they leave the guiding member and before they reach the tools. 40

3. A machine of the class described having, in combination, a reciprocatory setting tool, and a work guiding member having an unobstructed supporting surface leading to a point in line with the path of the tool and a pair of opposed parallel projections limiting the supporting surface of the work 45 guiding member, one of said projections being unobstructed throughout its length to permit a part of the work to be bent over it. 50

4. A machine of the class described having, in combination, oppositely arranged setting tools, an intermediate work plate adapted to be interposed between two layers of material and located in line with the tools, and a work guiding member at one side of the work plate for supporting both layers of 55 the work as it is fed to the tools. 60

5. A work guiding member for a fastener setting machine comprising a plate having a supporting surface, a longitudinal wall at one edge disposed perpendicularly to said surface, and a rib adjustably mounted adja- 65

cent to the other edge of said surface having an inner wall disposed perpendicular to the supporting surface and a rounded upper face upon which the work may be suspended. 70

6. A machine of the class described having, in combination, coöperating setting tools, and means for guiding to the tools the stiffened edge of a corset, said guiding means comprising a trough-shaped member 75 of substantially the width of the stiffened edge, one wall of said member being shaped to take under the stiffened edge and thus support the weight of the corset. 80

7. A machine of the class described having, in combination, coöperating setting tools, an edge gage adjustable toward and from the tools, a presser foot movable with the edge gage, and a work guiding member movable with the edge gage transversely 85 to the line of feed and having a work-supporting surface extending to a point remote from the setting tools. 90

8. A machine of the class described having, in combination, a transversely disposed die plate, tools for setting fasteners in two layers of work, one on each side of the die plate, and a work-supporting member arranged with its supporting face at one side of, and below, the lower face of the die 95 plate. 100

9. A machine of the class described having, in combination, coöperating setting tools one of which is movable transversely to feed the work, a stationary work plate disposed in the plane of movement of the movable setting tool, and an elongated work guiding member having a supporting face parallel to but below the plane of movement of the movable setting tool. 105

10. A machine of the class described, having, in combination, an elongated work guiding member, a stationary work plate located at one end of the guiding member, and a movable fastener setting and work feeding tool located beyond the work plate. 110

11. A machine of the class described having, in combination, an elongated work guiding member, a work plate located at one end of the guiding member with its lower work engaging face in a plane above the work supporting face of the guiding member, yielding means constructed and arranged to press the work upwardly against the work plate as it leaves the guiding member, and setting means located upon the side of the work plate opposite from the guiding member. 115

12. A machine of the class described, having, in combination, an elongated work guiding member, a work plate located at one end of said member with opposite work engaging faces disposed above the supporting surface of the guiding member, yielding presser feet for pressing one layer of material 125 130

against each side of the work plate as the two superposed layers pass from the guiding member, and setting tools arranged to act upon the work after it passes from the work plate.

13. A machine of the class described having, in combination, fastener setting tools arranged to act upon sheet material presented in an oblique position, an edge gage, and means for guiding the work to the setting tools including an open channel and co-operating members disposed at one end of the channel for engaging the opposite sides of the work, each having ribs inclined toward the edge gage relatively to the line of feeding movement.

14. A machine of the class described having, in combination, a setting die, and a die plate carrying a coöperating up-setting die having a projecting pilot, the die plate having a raised portion adjacent to the up-setting die arranged to engage the work and strip the same from the pilot when released by the setting die.

15. A machine of the class described having, in combination, a die plate having a raised portion, an upsetting die mounted in the die plate and having a pilot projecting beyond the surface of the die plate less than the raised portion on the die plate, and a setting die movable relatively to the upsetting die to clench a fastener in coöperation therewith.

16. A machine of the class described having, in combination, a punch, coöperating

setting dies one of which has a center spindle of greater diameter than the punch and a cupped end adapted to engage the margin of the perforation made by the punch after the punch has been withdrawn from the work, and actuating means for the punch and dies.

17. A machine of the class described having, in combination, a punch, coöperating setting dies, means for successively actuating the punch and dies, and means acting preliminarily to the setting operation for engaging and holding the margin of the perforation formed by the punch after the punch has been removed from the perforation.

18. A machine of the class described having, in combination, coöperating fastener setting tools, work feeding mechanism, and a member disposed with one end adjacent to the setting tools and having a gaging surface adapted to contact with the edge of the work as the work is fed to the setting tools and to determine the spread of the fasteners from the edge of the work, said gaging surface extending into proximity to the setting tools at one end and to a point remote from the setting tools at its other end.

In testimony whereof I have signed my name to this specification in the presence of two subscribing witnesses.

FRED A. RUMNEY.

Copies of this patent may be obtained for five cents each, by addressing the "Commissioner of Patents, Washington, D. C."

It is hereby certified that in Letters Patent No. 1,231,201, granted June 26, 1917, upon the application of Fred A. Rumney, of Boston, Massachusetts, for an improvement in "Fastener-Setting Machines," errors appear in the printed specification requiring correction as follows: Page 1, line 27, strike out the words "the provision of"; same page, line 83, for the word "interposing" read *interposed*; and that the said Letters Patent should be read with these corrections therein that the same may conform to the record of the case in the Patent Office.

Signed and sealed this 7th day of August, A. D., 1917.

[SEAL.]

F. W. H. CLAY,
Acting Commissioner of Patents
